UNITED STATES PATENT OFFICE.

HERMAN IHLENBURG, OF PHILADELPHIA, PENNSYLVANIA, ASSIGNOR TO THE
MACKELLAR, SMITHS & JORDAN COMPANY, OF SAME PLACE.

DESIGN FOR A FONT OF PRINTING-TYPE.

SPECIFICATION forming part of Design No. 21,607, dated June 7, 1892.

Application filed May 12, 1892. Serial No. 432,788. Term of patent 7 years.

To all whom it may concern:

Be it known that I, HERMAN IHLENBURG, a citizen of the United States, and a resident of Philadelphia, Pennsylvania, have invented a new and original Design for a Font of Printing-Type, of which the following is a specification.

My design for ornamental type is clearly shown in the accompanying typographical impression. The character of the type is what is known as "heavy-face ornamental type," all of the lines being of the same thickness. A general round effect is produced, being the essential feature of the design. The left-hand lines of the letters "A," "M," "U," "V," and "W" are curved inward, terminating in a knob, while the right-hand lines of the letters "B," "N," "M," "U," "V," "W," and "Y" are curved in the opposite direction, the right-hand line of the letters "B," "H," "K," "U," and "Y" terminating in a knob. The heads of the letters "A," "B," "C," "D," "E," "F," "G," "M," "N," "O," "P," "Q," "R," and "T" are rounded. The scroll lines

of the letters "C" and "D" terminate in a knob, and the scroll of the letter "P" also terminates in a knob. One of the cross-lines of the letter "X" is in the shape of an ogee curve, each end terminating in a knob. One or more of the terminals of the letters "E," "F," "G," "L," "T," and "Z" terminate in knobs. One of the lines of the letters "A," "B," "C," "F," "H," "J," "K," "M," "Q," "R," "S," "T," and "X" extend below the base-line of the font. The lower-case letters and numerals are in keeping with the upper-case letters.

I claim—

The design for a font of printing-type, as herein described, and as shown in the annexed typographical impression.

In testimony whereof I have signed my name to this specification in the presence of two subscribing witnesses.

HERMAN IHLENBURG.
